DESIGN FOR A SPRING-CLIP HANGER

George Yates, Glendale, Calif.

Application November 25, 1944, Serial No. 116,550

Term of patent 14 years

(Cl. D17—3)

To all whom it may concern:

Be it known that I, George Yates, a citizen of the United States and a resident of Glendale, California, have invented a new, original, and ornamental Design for a Spring-Clip Hanger, of which the following is a specification, reference being had to the accompanying drawing, forming part thereof.

Referring to the drawing:

Figure 1 is a perspective view of a spring-clip hanger, showing my new design;

Figure 2 is a side elevation of the device of Figure 1; and

Figure 3 is an elevational view of the back of the device of Figure 1.

I claim:

The ornamental design for a spring-clip hanger, as shown.

GEORGE YATES.
